United States Patent Office

Des. 186,898
Patented Dec. 22, 1959

186,898

REEL

Walter Uebelhoer, Snyder, N.Y., assignor to Marwal
Products Corporation, Buffalo, N.Y.

Application July 17, 1958, Serial No. 51,821

Term of patent 14 years

(Cl. D41—1)

FIG. 1

FIG. 2

Fig. 1 is a top perspective view of a reel, showing my new design;

Fig. 2 is a side elevational view thereof, taken from the top of Fig. 3;

Fig. 3 is a top plan view thereof;

Fig. 4 is a side elevational view of the reel taken from the bottom of Fig. 3; and

Fig. 5 is a side elevational view thereof taken from the right of Fig. 4.

I claim:

The ornamental design for a reel, substantially as shown.
